APPARATUS FOR SLICING MEATS,
CHEESE, ETC.

Edward J. Neary, St. John's, Newfoundland

Application August 7, 1935, Serial No. 35,020

4 Claims. (Cl. 146—138)

The object of the present invention is to provide a simplified type of slicing apparatus, a characteristic of which is that the thickness of slice is determined by adjustment of the knife guiding means.

A further object of the invention is to provide a novel type of sharpening means for the knife so arranged as to follow the knife guiding means in the adjustments of the latter.

These, and other objects of the invention will be described with reference to the accompanying drawings, in which:

Figure 1 is a perspective view of an embodiment of the invention.

Figure 2 is a longitudinal sectional elevation on the line 2—2, Fig. 6.

Figure 3 is a fragmentary vertical section on the line 3—3, Fig. 5.

Figure 4 is a horizontal fragmentary section on the line 4—4, Fig. 5.

Figure 5 is a front elevation of the device showing in full lines the knife in upper positions and in dotted lines in intermediate position.

Figure 6 is a horizontal section on the line 6—6, Fig. 2, looking in the direction of the arrows.

Figure 7 is an enlarged fragmentary section on the line 7—7, Fig. 6.

Figure 8 is a sectional elevation on the line 8—8, Fig. 2, looking in the direction of the arrows.

Referring to the drawings, the embodiment of the invention therein shown comprises a box-like base 1, having an upper horizontal support 1x for the article to be cut. Side pieces 2, 2x are provided, and, if desired, these side pieces may be vertical flanges of a sheet metal supporting member applied to member 1x, as indicated in Fig. 8.

Secured to horizontal support 1x in any suitable manner, is a guide frame comprising the uprights 3 which are connected by an A-shaped connecting member 3x which may be integral with members 3. The cross bar 4 of connecting member 3x is provided with a vertical apertured boss to afford a seat for a guiding rod 5 and the rod passes through a second boss 6 at the top of member 3x. The rod is held in fixed position by such means.

Slidably mounted upon the rod 5 is a sleeve 7 exteriorly formed with a ball-shaped member 7x embraced by the extension 8x of an arm 8, the said extension 8x having an aperture shaped to conform with the curvature of the ball. To this end the extension 8x is in two parts, the upper

part being a detachable plate as shown in Figs. 1 and 3.

Arm 8 is secured to a knife 9 having a handle 10, the knife being guided in its downstroke by the adjacent vertical edges of uprights 3 and arms 11. The knife forwardly of uprights 3 is faced by the vertical adjustable arms 11. Arms 11 at their upper ends are provided with guide fingers 12 which abut the side walls of uprights 3, and each arm at its base is provided with an integral horizontal section 11x, the two horizontal sections being joined by a cross bar 13. Cross bar 13 is formed with a threaded aperture to receive an adjusting screw 14 which passes through a boss 15 in member 1 and is provided with an operating thumb wheel 16. The part of this screw that passes through boss 15 is slightly longer in diameter than the threaded part and is allowed free longitudinal movement through boss 15. By rotation of the screw, thumb wheel 16 will be caused to move forward or from wall 1xx of the base member thus regulating the amount of forward movement allowed arms 11. The horizontal sections 11x of the arms are guided in their movements by being placed in the channelways of guide blocks 18, Figs. 6 and 8, the guide blocks being provided with cover plates 19.

Adjacent each arm 11 is a knife sharpener element 20 which may be of such material, as, for example, metal, as will automatically maintain the cutting edge of the knife in sharp condition through its movements in cutting and in retraction from cutting position. Each knife sharpener is affixed to a horizontal arm 20x guided within the channelway of a guide block 21 which lies adjacent block 18.

I prefer that each arm 20 be engaged by a spring 22 and in order to insure equal tension 40 upon the sharpeners the springs may be connected by a cable 23 which runs over pulleys 24 (Fig. 6). Hooks 11xx are also provided in parts 11x so that the operator may at will connect the springs thereto and release sharpeners. 45

The end of each sharpener 20 may be provided with a laterally extending flange 25 for receiving an abutment stud 26 which engages one of the arms 11. Studs 26 may be threaded in flanges 25 if desired. 50

In the operation of the device, the amount of movement allowed arms 11 will determine the thickness of the slice by the adjustment of the screw. In practice, the blade will be lowered and the block of meat, cheese, or other object to be 55

sliced will be pressed forward with the knife as an abutment so that the knife in turn will be moved forward to the extent permitted by the thumb wheel 16 taking with it arms 11. Handle 10 is then grasped and the knife moved upwardly above the top surface of the article to be cut, and as the blade clears the top of the article to be cut the arms 11, being pulled back by the tension of the springs, press the blade of the knife against the edges of guides 3 and keep them close to it all through the downward or cutting movements. Hence, in the initial stroke the knife will be back from the front face of the article to be cut a distance regulated by the amount of play allowed arms 11 and the thickness of the slice may be of any desired degree. The position of the knife in the act of cutting is shown at 9, Fig. 2. As the knife passes down within the range of the inclined sharpeners 20, its cutting edge will be engaged by the sharpeners if they are hooked up to springs 22. The movement of the knife is in reality a bodily arcuate movement. It will be pulled forwardly by means of handle 10 until a stop 27 engages the adjacent arm 11 and then will begin a bodily downward arcuate movement, the ball and socket connection with the guiding rod 10 permitting said movement. After each cutting stroke with the knife in lowermost position, the article to be cut is moved forwardly against the knife as an abutment and the knife will be moved again forward taking arms 11 with it to the extent allowed by the adjustment of the screw. When the knife is swung upwardly above the article to be sliced, the knife will again lie in the position shown in Fig. 2 with its face directly abutting uprights 3.

It will be understood that various modifications may be made in the form of the embodiment illustrated in the drawings without departing from the spirit of the invention. I have shown the plate carrying guide bars 2, 2x, as dovetailed in grooves formed on the upper surface of support 1x so that the plate may be readily removed for cleaning or sterilization.

Having described my invention, what I claim and desire to secure by Letters Patent, is as follows:

1. In a slicing apparatus, a support for an object to be sliced, a knife mounted for reciprocal movement and for movement in directions transversely of said movement, a vertical guide for

one side of said knife determining the line of cut, a second vertical guide for the opposite side of the knife, knife sharpening elements, means for limiting movement of said second vertical guide toward and from the first guide to determine the thickness of slice, and connections between the second vertical guide and the knife sharpening means whereby the latter is actuated by said adjusting means. 5

2. In a slicing apparatus, a support for an object to be sliced, spaced knife guides rising vertically from said support at the forward end thereof, a vertically extending guide rod carried by said guides, an arm having an aperture receiving said guide rod, a knife connected to the arm, a vertical knife guide device disposed forwardly of the first-named guides, a screw mechanism for limiting the movement of said guide device toward and from the first-named guides, knife sharpening members disposed adjacent the first-named guides, spring tension means for said sharpening members and outer guides, and connections between the sharpening members and the said knife guide device whereby movements of the latter are transmitted to the sharpening members and vice versa. 10 15 20 25

3. In a slicing apparatus, a box-like support for an object to be sliced, spaced knife guides rising vertically from said support at the forward end thereof and a vertically extending guide rod carried by said guides, an arm having connections with said guide rod and adapted for universal movement relative thereto, a knife connected to the arm, vertically extending knife guiding arms disposed forwardly of the first-named guides, said arms having extensions within the box-like casing, a connecting member for the extensions, and a screw device engaging said connecting member for limiting the movement of the said guide arms, and sharpening members connected to horizontally extending carriers disposed within the casing, spring tension means for said sharpening members and forward guides, and means whereby the sharpening members may receive adjustment as to position. 30 35 40 45

4. A device constructed in accordance with claim 3, in which the carriers for the sharpening members are slidably mounted within the casing, spring tension means for each carrier, and an equalizing connection between the springs. 50

EDWARD J. NEARY.
